UNITED STATES PATENT OFFICE

RICHARD A. ZEIDLER, OF SECAUCUS, NEW JERSEY, ASSIGNOR TO PASS & SEYMOUR, INC., OF SYRACUSE, NEW YORK, A CORPORATION OF NEW YORK

DESIGN FOR A CEILING FIXTURE

Application filed June 7, 1930. Serial No. 35,975. Term of patent 14 years.

To all whom it may concern:

Be it known that I, RICHARD A. ZEIDLER, a citizen of the United States, and resident of the city of Secaucus, county of Hudson, State of New Jersey, have invented a new, original, and ornamental Design for Ceiling Fixtures, of which the following is a specification, reference being had to the accompanying drawing, forming a part thereof, and in which—

I claim:

The ornamental design for a ceiling fixture, as shown.

RICHARD A. ZEIDLER.
